EJECTOR FOR EJECTING PRINTED ARTICLES FROM A PRINTING MACHINE

Joseph Krell, Berlin-Zehlendorf, Germany, assignor to Adrema Maschinenbauges m. b. H., Berlin, Germany

Application February 7, 1938, Serial No. 189,199
In Germany February 27, 1937

7 Claims. (Cl. 271—84)

My invention relates to ejectors for ejecting printed articles of any kind, such as envelopes, sheets, forms, etc., from printing machines.

It has already been proposed in address-printing machines to arrange an ejector rod which is mounted to reciprocate in axial direction on the table of the machine and is operatively connected to the driving mechanism of the machine for moving it in forward, i. e., ejecting direction, and equipped with a spring for moving the rod in backward direction into its initial position.

My invention relates to improvements in machines of this type, it being understood, however, that I am not limited to address-printing machines.

One of the objects of my invention is to provide an ejector which is more simple and reliable than the ejectors as designed heretofore.

To this end, in combination with an ejector rod arranged as described, I provide a striker lever which is fulcrumed on the frame of the machine, means which will be shown and described, by way of example, as a striker on the lever, and an adjustable clamp on the ejector rod, for transforming the forward circular movement of the striker about the fulcrum of the striker lever into straight-line forward movement of the rod, and a striker spring arranged to move the striker lever in the direction of the forward movements.

A member is arranged on the printing arm for depressing the striker lever against the action of the striker spring during the descent of the printing arm, thus putting the striker spring under tension. The striker lever is locked in its depressed position by a pawl, and means which will be shown and described, by way of example, as the projecting end of a circular cam, is arranged on the pawl to be engaged by the member during the ascent of the printing arm, for disengaging the pawl from the striker lever which now, under the reaction of the strong striker spring, throws the ejector rod into its ejecting position.

It is another object of my invention to provide improved means for holding the ejector against operation during the skipping of printing plates.

To this end, in combination with the means aforesaid, I provide mechanism which is operatively connected to the skipping means of the printing machine and holds the striker lever in its depressed position notwithstanding its release by the pawl.

Other objects of my invention will appear from the following detailed description, with reference 55 to the accompanying drawings in which I have

illustrated my ejector, by way of example, as adapted to an address-printing machine.

In the drawings.

Fig. 1 is a perspective illustration of the ejector as arranged on the table of the machine. 5

Figs. 2, 3, and 4 are perspective detail illustrations of the ejector, drawn to a larger scale and showing, respectively, the initial or normal position of the ejector, an intermediate position, and the position after the ejector rod has completed its forward movement.

Referring now to the drawings, 1 is the table of the address-printing machine, 2 is its oscillating printing arm, 3 is the printing head at the free end of the arm, and 4 is the printing pad on the head 3. 4' is a hopper for a supply of printing plates 5 which are intermittently moved to the printing station 5' along a track 6, so that a printing plate is presented to the head 3 at the printing station for every cycle 10 of the machine. The mechanisms for oscillating the printing arm 2, for feeding the printing plates, and for skipping certain plates, are old and have not been illustrated. 15

A frame having a block 14 at its front, and a block 15 at its rear end, is secured on the table 1 at the rear. An ejector rod 13 is mounted to slide in bores of the blocks with its rear end, and the vertical flange 12 of an angular ejector bar is secured to its front end. The ejector rod extends 25 in parallel relation to the track 6 and the table 1, and the ejector bar extends transversely to the track and is supported on the table by its horizontal flange 11. The flange 11 is folded, as best seen in Figs. 2, 3, and 4, to form a pocket 30 for the reception of a similar fold 10 at the rear end of a horizontal tray 8. The fold 10 is inserted in the pocket 11 in the direction of the arrow 41 in Fig. 1, and, to facilitate the introduction, the upper flange of the pocket 11 is cut 40 away at an angle of 45 dgs. at 42. At its opposite end, the pocket is flattened at 43 to limit the inward movement of the fold 10 in the pocket 11, or a check, not shown, is arranged at this end. The tray 8 is made of any suitable material, for instance, press-spahn, and has a rectangular hole for the printing plate which is at the printing station 5'. The article to be printed, in the present instance an envelope 7 shown in dot-and-dash lines, is placed on the tray 8 and printed upon the subsequent descent of the printing head, unless skipped. The location of the envelope is facilitated by lines at right angles to each other, and/or locating lugs 9 may be pasted to the tray. 45

It may be desirable to use as the tray a metal foil on paper or press-spahn, for instance, a mat aluminium foil which has the advantage that it can be written or drawn on.

Since the articles are placed on the tray 8, and 5 the tray is secured to the angle bar 11, 12, it is an obvious impossibility that they might get under the bar. In order to prevent articles from getting under the tray 8 when pushed toward it in the direction of the arrow 41, a strip or 10 straight-edge 40 is secured to the table 1, with one of its sides secured to the table, and with its other side overlapping the corresponding side of the tray.

It will appear from this that the tray, being 15 connected to the bar 11, 12, partakes in the reciprocation of the bar, and that the bar extends transversely to the track 8 for the printing plates 5, and is supported on the table 1.

As described, the ejector bar 11, 12 is secured to 20 the ejector rod 13 which is mounted to slide in its longitudinal direction and in parallel relation to the table in the two blocks 14, 15 of the frame on the table. 16, Figs. 2, 3, and 4, is a clamp which is adjustably mounted on the rod 13 25 between the blocks 14 and 15, and equipped with a suitable screw for holding it on the rod. 19 is a pull-back spring placed about the rod 13 between the clamp 16 and the front block 14. The spring tends to hold the clamp 16 against the rear block 30 15. In the normal or initial position of the ejector, Fig. 2, a buffer rod 33 at the rear of the clamp, best seen in Fig. 4, bears against a buffer of felt, leather, or other resilient material 34 in a bore 35 of the rear block 15. A similar rod 38, for cooperation with a buffer 39 in a bore of the front block 14, is arranged at the front of the clamp.

Obviously, the movement of the ejector is a function of the size of the articles placed on the tray 8. The larger the size, the shorter must be the distance between the front block 14 and the bar 11, 12 in the initial position Fig. 2. To regulate the throw of the ejector, the screw of the clamp 16 is loosened and, while the clamp is held 40 against the buffer 34 in the rear block 15 by the pull-back spring 19, the ejector rod 13 is pulled to the rear through the clamp as far as required, and the clamp is then re-set by its screw. By these means, the ejector bar 11, 12 is held in the proper position with respect to the printing 45 station 5' in conformity with the size of the articles to be printed, in the initial position of the ejector.

44 is an angular dog which is pivoted on the clamp at 43. A spring, not shown, tends to urge 50 the horizontal arm of the dog in upward direction, and this movement is limited by the vertical arm 45 of the dog bearing against the front face of the clamp 16.

55 22 is a sector-shaped striker lever which is fulcrumed on the frame of the blocks 14, 15 at 23. 30 is a strong striker spring which is secured to the lever 22 at 30' with one of its ends. The other end of the spring is anchored on the front block 14 at 29. The arrangement of the striker 60 spring is such that in the initial position of the striker as shown in Fig. 2 the axis of the spring extends through the axis of the fulcrum 23 about which the striker lever 22 oscillates.

70 21 is a striker at the lower end of the striker lever 22 which in the initial position bears against the back of the horizontal arm of the dog 44. 24 is a lug at the upper end of the striker lever 22, and 25 is a pawl which is fulcrumed on the frame 75 of the blocks and cooperates with the lug 24.

At its upper end the pawl is made with a concave camming face 35 curved to an arc of a circle about the axis of the fulcrum 23. 26 is a step at the lower end of the camming face 35, and 27 is a spring secured to the pawl 25 and anchored in the frame at 28, for pulling the pawl toward the striker lever 22.

In the normal position illustrated in Fig. 2, the ejector is at the rear end of its stroke and the camming face 35 of the pawl 25 is held against the lug 24 by the spring 27. 31 is an operating member on the printing arm 2, of angular configuration and secured by a screw. When the printing arm 2 descends from its elevated position, Fig. 1, the member 31 whose elevated position is also shown in Fig. 2, descends with it, clearing the upper end of the pawl 25 but engaging, and depressing, the lug 24 and turning the striker lever 22 in downward direction against the action of the striker spring 30, as indicated by the arrow 32. Finally, as shown in Fig. 3, the lug 24 engages below the step 26 and the pawl 25 which heretofore had not moved on account of the concentricity of its camming face 35 with the arc described by the end of the lug 24, is now turned against the arrow 35'. This movement of the striker lever occurs against the striker spring 30 which is now under strong tension, the striker lever 22 being locked by the step 26 of the pawl. The upper end of the pawl is now in the path 30 of the re-ascending member 31, and the striker 35 21 is clear of the dog 44, 45.

While the parts of the ejector are in the intermediate position Fig. 3, the envelope or the like 7 on the tray 8 is printed. After this operation has 35 been performed by the printing plate at the station 5', the printing arm 2 ascends to return into its initial position, Fig. 1. The member 31 which, during its descent, moved clear of the upper end of the pawl 25, now engages this end, Fig. 4, and 40 turns the pawl in the direction of the arrow 35'. Fig. 3, against its spring 27. The step 26 of the pawl now releases the lug 24 on the striker lever 22, and the strong spring 30 abruptly returns the lever 22 into its initial position, as shown in 45 Fig. 4. When the member 31 has moved past the upper end of the pawl 25, Fig. 2, the spring 27 again holds the pawl against the lug 24 with its camming face 35, ready to lock the striker lever upon the next descent of member 31.

When the striker lever 22 is thrown over abruptly, as described, by its striker spring 30, the 50 striker 21 strikes the arm 44 of the dog on the clamp 16 a smart blow, throwing in the direction of arrow 37, Fig. 3, the ejector rod 13, the ejector bar 11, 12, and the tray 8 while the pull-back spring 19 is compressed by the clamp 16 moving toward the front block 14, Fig. 4. This jerks, in manner per se known, the printed envelope 7 away from the machine in the same direction 37, and into a suitable container. Noise is suppressed by the buffer rod 38 at the clamp 16 striking the buffer 39 in the front block 14, and the movement of the ejector rod 13 in the direction of arrow 37 is arrested.

Immediately after the momentum of the ejector has become exhausted, and the bar 11, 12 and rod 13 have been arrested, the pullback-spring 19 which had been compressed, returns the parts into the position shown in Fig. 2. It will be understood that during the ejecting movement in the direction of arrow 37 the striker lever 22 is rocked only through an angle corresponding to the movement of the lever from the position in Fig. 3 into the position in Fig. 4, or Fig. 2. The 75

lower end of the striker 21 has been elevated so far as to clear the arm 44 of the dog which now returns into its position below the striker so that the striker cannot strike the arm 44. In its rear final position the clamp 16 is arrested without noise by the buffer 34 in the rear block 15.

5 The ejector is now ready for another operation which occurs upon the subsequent descent of the printing arm 2 for printing the printing 10 plate which in the meantime has arrived at the printing station 5'.

10 If, however, this printing plate is one to be skipped, the striker lever 22 is locked against returning into its initial position, Fig. 4, from the 15 intermediate position, Fig. 3, by the mechanism which will now be described.

15 The mechanism is equipped with a shaft 18 arranged in parallel relation to the ejector rod 13, and mounted to rotate in bearings forming part of the blocks 14 and 15. The clamp 16 is grooved to clear the shaft. 46 is a crank at that end of the shaft 18 which projects from the front block 14 in the direction toward the printing station, and 47 is a coiled spring placed on the crank 20 pin and connected to a pin 48 on the arm 49 which forms part of the skipping mechanism. On the opposite end of the shaft 18 is keyed a locking bolt 50 for cooperation with a stud 51 on the striker lever 22.

25 30 While the skipping mechanism is inactive, i. e., in such position that the plates are printed at the station 5', pressure is exerted on the arm 49 in the direction of the arrow 52 in Fig. 2, that the bolt 50 is clear of the stud 51, and does not interfere with the oscillation of the striker lever from the position Fig. 3 into the position in Figs. 4 and 2.

35 If the plate at the printing station is one to be skipped, the control of the skipping mechanism moves the arm 49 against the arrow 52 during the descent of printing arm 2, the crank 46 turns the shaft 18 in the same direction, and the bolt 50 is moved toward the striker lever 22 when the parts are in the position Fig. 3, arresting the 40 stud 51 and preventing upward movement of the striker lever 22 by its spring 30 notwithstanding its release by the pawl 25. The lever consequently cannot move from the intermediate position 45 Fig. 3 into the position Fig. 4, the ejector is not operated by the striker 21, and the non-printed envelope 7 remains at the printing station until it has been printed, i. e., as soon as a plate to be 50 printed has arrived at the station 5' and the bolt 50 has again been moved clear of the stud 51 on 55 the striker lever 22.

55 The locking mechanism just described is dispensed with in machines of the type in which the printing arm remains in its elevated position when a printing plate is skipped, provided that 60 each printing plate is to be printed a single time only, as the ejector in this machine is not operated when a plate to be skipped is at the printing station.

65 If it is desired to render the ejector inactive, the member 31 at the printing arm 2 is removed or so adjusted that upon its descent it will miss the lug 24 of the striker lever 22. The adjustment is effected by turning the member 31 through 90 degs. about its screw on the printing 70 arm 2, as shown in dotted lines in Fig. 1.

I claim:

75 1. In an ejector for ejecting printed articles from a printing machine, an oscillating printing arm, a frame, an ejector rod mounted to slide in the frame, a striker lever fulcrumed on the frame,

means for abruptly transforming the forward circular movement of the striker lever into forward straight-line movement of the ejector rod, a spring for returning the ejector rod into its initial position, a striker spring arranged to move the striker lever forward against the action of the return spring, a member on the printing arm for depressing the striker lever against the action of the striker spring during the descent of the printing arm, a pawl for locking the striker lever in its depressed position, means on the pawl adapted to be engaged by the member during the ascent of the printing arm, for disengaging the pawl from the striker lever, and mechanism operatively connected to the skipping means of the printing machine for holding the striker lever in its depressed position notwithstanding its release by the pawl.

2. In an ejector for ejecting printed articles from a printing machine, an oscillating printing arm, a frame, an ejector rod mounted to slide in the frame, a striker lever fulcrumed on the frame, means for abruptly transforming the forward circular movement of the striker lever into forward straight-line movement of the ejector rod, a spring for returning the ejector rod into its initial position, a striker spring arranged to move the striker lever forward against the action of the return spring, a lug on the striker lever, a member on the printing arm for engaging the lug and depressing the striker lever against the action of the striker spring during the descent of the printing arm, a pawl, a step on the pawl for engaging the lug and locking the striker lever in its depressed position, and means on the pawl adapted to be engaged by the member during the ascent of the printing arm, for disengaging the step from the lug.

3. In an ejector for ejecting printed articles from a printing machine, an oscillating printing arm, a frame, an ejector rod mounted to slide in the frame, a striker lever fulcrumed on the frame, an adjustable clamp mounted on the ejector rod, a dog fulcrumed on the clamp, a striker on the striker lever for engaging the dog, and abruptly throwing forward the ejector rod, a spring for returning the ejector rod into its initial position, inserted between the clamp and the frame, a striker spring connected to the striker lever for turning the lever so as to throw the striker of the lever against the dog, a member on the printing arm for depressing the striker lever against the action of the striker spring during the descent of the printing arm, a pawl for locking the striker lever in its depressed position, and means on the pawl adapted to be engaged by the member during the ascent of the printing arm, for disengaging the pawl from the striker lever.

4. In an ejector for ejecting printed articles from a printing machine, an oscillating printing arm, a frame, a pair of spaced-apart blocks on the frame, an ejector rod mounted to slide in the blocks, an adjustable clamp mounted on the ejector rod between the blocks, buffers on the blocks, buffer rods at opposite ends of the clamp for engaging the buffers, a striker lever fulcrumed on the frame, a dog fulcrumed on the clamp, a striker on the striker lever for engaging the dog, and abruptly throwing forward the ejector rod, a spring for returning the ejector rod into its initial position, inserted between the clamp and one of the blocks, a striker spring connected to the striker lever for turning the lever so as to throw the striker of the lever against the dog, a member on the printing arm for depressing the

striker lever against the action of the striker spring during the descent of the printing arm, a pawl for locking the striker lever in its depressed position, and means on the pawl adapted to be engaged by the member during the ascent of the printing arm, for disengaging the pawl from the striker lever.

5. In an ejector for ejecting printed articles from a printing machine, an oscillating printing arm, a frame, an ejector rod mounted to slide in the frame, a tray including a metal foil and secured to the rod for the reception of the articles, a striker lever fulcrumed on the frame, means for abruptly transforming the forward circular 10 movement of the striker lever into forward straight-line movement of the ejector rod, a spring for returning the ejector rod into its initial position, a striker spring arranged to move the striker lever forward against the action of the return spring, a member on the printing arm 15 for depressing the striker lever against the action of the striker spring during the descent of the printing arm, a pawl for locking the striker lever in its depressed position, and means on the pawl adapted to be engaged by the member during the ascent of the printing arm, for disengaging the pawl from the striker lever.

6. In an ejector for ejecting printed articles from a printing machine, an oscillating printing arm, a frame, an ejector rod mounted to slide in the frame, an angular ejector bar secured to the rod, a fold formed by the horizontal flange of the bar, a tray for the reception of the articles, a fold on the tray adapted to be inserted in the 20 fold of the horizontal flange, a striker lever fulcrumed on the frame, means for abruptly transforming the forward circular movement of the 25 printing arm, a pawl for locking the striker lever in its depressed position, and means on the pawl adapted to be engaged by the member during the ascent of the printing arm, for disengaging the pawl from the striker lever.

striker lever into forward straight-line movement of the ejector rod, a spring for returning the ejector rod into its initial position, a striker spring arranged to move the striker lever forward against the action of the return spring, a member on the printing arm for depressing the striker lever against the action of the striker spring during the descent of the printing arm, a pawl for locking the striker lever in the depressed position, and means on the pawl adapted to be engaged by the member during the ascent of the printing arm, for disengaging the pawl from the striker lever.

7. In an ejector for ejecting printed articles from a printing machine, a table, an oscillating printing arm above the table, a frame on the table, an ejector rod mounted to slide in the frame in parallel relation to the table, a straight-edge secured to the table and overlapping that side of the tray toward which the articles are introduced, a striker lever fulcrumed on the frame, means for abruptly transforming the forward circular movement of the striker lever into forward straight-line movement of the ejector rod, a spring for returning the ejector rod into its initial position, a striker spring arranged to move the striker lever forward against the action of the return spring, a member on the printing arm for depressing the striker lever against the action of the striker spring during the descent of the printing arm, a pawl for locking the striker lever in its depressed position, and means on the pawl adapted to be engaged by the member during the ascent of the printing arm, for disengaging the pawl from the striker lever.

JOSEPH KRELL.
